ABSTRACT OF THE DISCLOSURE

Rectangular screen whose frame is provided at each edge with a rotatable rod anchored to a respective edge of a perforate sheet which is stretched across the frame, rotation of any rod serving to tension the sheet in a direction perpendicular to the rod axis.

This invention relates to plansifters and similar equipment.

Plansifters and similar equipment incorporate a number of screens or sieves, each screen or sieve including a frame over which a metal gauze or other woven material is stretched.

While the equipment is in use, the gauze stretches and has to be subsequently re-tensioned. This operation has been a difficult one hitherto, particularly because the small amount of space left free at the outside of the frame prevents the fitting of any complicated means of anchorage for the gauze.

The object of the present invention is to provide a screen for use in a plansifter or like equipment, in which the gauze of the screen can be tensioned very simply and effectively.

According to the present invention there is provided in a screen a frame comprising elongate members defining the outline of the screen, one of said members having a longitudinal groove therein, a perforate flexible sheet having edges, said sheet being stretched across said frame, an elongate element seated in said groove around which one of said edges is wound until said sheet is stretched across the frame to give a required degree of tightness, and means for locking against rotation said elongate element in said groove, the latter means being advantageously disposed at one end of said elongate element.

When the rod or other elongate element is turned, the gauze or other perforate sheet is wound up and is thus stretched. As the groove or other elongate recess is situated at least partially in the supporting face of the side of the frame, the gauze reaches the rod, to all intents and purposes, without passing over any sharp edges and is therefore uniformly tensioned.

In one advantageous embodiment of the invention the means whereby the rod is immobilized or otherwise locked are provided at one of its ends. For example, the rod may be circular in cross-section, except at one end, where it is of polygonal cross-section and carries a ferrule with a projecting tab.

In this case, the groove may be provided in the angle formed by the supporting face and the outer side face of the frame. The two sides of the groove should preferably be at an angle of less than 90° to each other.

Alternatively, the rod may be polygonal in cross-section and is immobilized within the groove by a plate fixed to the frame and covering the groove.

Each edge of the gauze may simply be wound around its associated rod, its attachment to the rod depending on friction. It is preferable, however, to provide positive fixing, which, according to a further feature of the invention, is achieved by means of an adhesive tape. This should

2

preferably be of the "transfer" type, i.e. adhesive on both sides, which enables the rod to adhere.

Certain embodiments of screens in accordance with the invention will now be described, by way of example, with reference to the accompanying diagrammatic drawings, in which:

FIG. 1 is a plan of part of the frame of one embodiment of a screen according to my invention;

FIG. 2 is a view, drawn to an enlarged scale, showing details of part of the frame of FIG. 1, with groove cappings or covering strips omitted;

FIG. 3 is a cross-section on the line III—III of FIG. 2;

FIG. 4 is a section similar to FIGURE 3 but shows a second embodiment of the screen;

FIGS. 5 and 6 are also sections similar to FIG. 3 but show two further embodiments;

FIG. 7 is a cross-section on the line VII—VII of FIG. 2;

FIG. 8 is a perspective view showing how the gauze may be attached to each of the rods of the screen with adhesive tape; and

FIG. 9 is a cross-section showing how tape of "transfer" type may be used for fixing the gauze to one of the rods.

The screen illustrated in FIGS. 1—3 and 7 comprises a wooden or metal frame 1, over which a metal gauze (or a natural or synthetic woven material) 2 is stretched.

Each member of the frame 1 has a groove or other elongate recess 3, of square section in the example illustrated, at the angle formed by the supporting face of the frame, here assumed to be the upper face, with the outer side face of the frame. The corresponding edge of the gauze 2 is wound round and fixed to a rod or other elongate element 4, which fits into the groove 3. The rod 4 is circular in cross-section, except at one end 4a, where it is of square section, and is secured in the desired position by a tab 5 on a ferrule fitted over its square end, which tab bears against a recess 9 in the frame.

The gauze is tensioned by rotation of each of the rods 4 with the aid of a suitably shaped spanner until the desired tension is obtained, whereupon a locking means in the form of the ferrule-carrying tab 5 is slipped over the square-section end of the rod.

The gauze 2 then exerts a force holding each of the rods 4 onto an inner face 3a of the groove 3. In this way, the rods are held in their grooves with little likelihood of being dislodged. As seen in FIG. 3, the plane of the upper face of frame 1 is substantially tangent to rod 4 whereby the gauze 2 can be wound up without scraping against an edge of the frame.

As a further safeguard, the two sides of the groove 3 may include an acute angle with each other, as shown in FIG. 4 where the modified frame has been designated 1'.

For the sake of appearance and cleanliness, the groove 3 may be covered with a capping 6 shown in FIG. 3 as an angle member, which may for example simply be fitted over the edge of the frame.

The embodiment shown in FIG. 5 differs from that illustrated in FIG. 3 only in that the groove 3 is provided in the upper face of the side of the frame 1, capping 6' being here a flat cover plate screwed to this frame in cantilever fashion.

In the embodiment shown in FIG. 6, rod 4' is polygonal or square in cross-section throughout. The groove 3 is provided in the upper face of the frame and contains a resilient bed 7.

The torque exerted by the gauze 2 and the resilient bed tends to force one edge of the rod 4' against the groove face 3a and another edge against the capping 6', which is necessary in this embodiment to prevent the rod from turning. To increase the tension on the gauze, the

rod is rotated with the aid of a spanner slipped over one of its ends; the rod moves down in the groove, compressing the resilient bed 7, until the edge originally bearing against the face 3a is clear of capping 6'. The spanner is then released, whereupon this edge is now forced against the capping, locking the rod in its new position.

As already stated, if the rod 4 or 4' and the gauze 2 have sufficiently high coefficients of friction, the gauze may be secured to the rod by friction if wound around a sufficient number of times. It is better, however, to fasten the gauze to the rod. Adhesive tape may be used for this purpose.

In FIG. 8, adhesive tape 8 has one part fixed to the rod 4, the gauze 2 then being stuck to the remaining part of the tape while being stretched lengthwise, as indicated by arrows f_1 . This pre-stretching avoids the formation of wrinkles in the gauze when this is subsequently stretched in the direction of arrow f_2 by the rotation of the rod 4.

In FIG. 9, transfer tape 8', coated with adhesive on both faces, has been stuck to the rod 4. All that remains to be done is to apply the gauze 2, while keeping it stretched, to the rod 4, which has itself thus been rendered adhesive.

It should be emphasized that the invention is not limited to the embodiment described and illustrated here, but includes all modifications thereof fairly embraced by the language of the appended claims.

What is claimed is:

1. In a screen, in combination:

A frame comprising elongate members defining the outline of the screen, at least one of said members having a longitudinal groove therein; a cover member on said frame overlaying said groove; a perforate flexible sheet stretched across said frame; an elongate element rotatably seated in said groove in

engagement with an edge of said sheet for tightening same across the frame; and locking means for holding said elongate element against rotation in said groove, said locking means including resilient means in said groove biasing said element against said cover member.

5 2. The combination defined in claim 1 wherein said cover member is a cantilevered plate.

10 3. The combination defined in claim 2 wherein said resilient means comprises a layer parallel to said plate, said element being a polygonal rod sandwiched between said layer and said plate.
